UNITED STATES PATENT OFFICE.

WILLIAM C. BRUZGA, OF NORWOOD, MASSACHUSETTS.

TOBACCO USER'S APPLIANCE.

Application filed February 25, 1921. Serial No. 447,722.

To all whom it may concern:

Be it known that I, WILLIAM C. BRUZGA, a citizen of the United States, residing at Norwood, in the county of Norfolk and 5 State of Massachusetts, have invented certain new and useful Improvements in Tobacco Users' Appliances, of which the following is a specification.

This invention relates to smokers' appliances and the primary object of the invention is to provide a novel holder for cigarettes and the like, which is so constructed as to present the appearance of a cigar and to give the impression of a cigar being 15 smoked instead of a cigarette.

Another object of the invention is to provide a novel holder for cigars and cigarettes which will prevent the falling of the ashes from the cigar or cigarette upon the 20 ground and which will permit the quick and ready placing of a cigar or cigarette within the holder.

A further object of the invention is the provision of a novel holder and casing for 25 cigars and cigarettes embodying a novel type of bit for receiving the cigar or cigarette, a novel type of combustion chamber for enclosing the cigar or cigarette, and a novel means for uniting the combustion 30 chamber and the bit together, to permit the correct and easy connection and disconnection thereof, and to hide the point of connection between the combustion chamber and the bit, so that the holder and casing will give the appearance of being formed 35 in a single piece.

With these and other objects in view, the invention consists in the novel construction, arrangement and formation of 40 parts, as will be hereinafter more specifically described, claimed and illustrated in the accompanying drawings, forming a part of this specification, in which:

Figure 1 is a side elevation of the improved cigar and cigarette holder and casing.

Figure 2 is a longitudinal section through the same showing a cigarette positioned therein.

Figure 3 is a side elevation of the improved combined holder and casing illustrating the combustion chamber and the bit disconnected from each other, and

Figure 4 is a detail transverse section 55 taken on the line 4-4 of Figure 2.

Referring to the drawings in detail, wherein similar reference characters designate corresponding parts throughout the several views, the letter A indicates the bit portion of the improved combined 60 cigarette holder and casing; B, the combustion chamber and C the cigarette positioned therein.

The bit A may be formed of any preferred material, such as wood, rubber, or 65 the like, painted, stained and grained to present the appearance of the butt portion of a cigar and is provided with a nipple 6, so as to form a mouth piece, whereby the holder can be readily held in the mouth. 70 The body 5 of the portion A is provided with the longitudinally extending bore 7, the inner end of which is gradually enlarged as at 8, and has secured therein the metallic nipple 9, which is adapted to receive 75 the cigarette C. The outer end of the nipple may be provided with a guard flange 10, so as to overlie the inner surface of the body 5, and thereby prevent the burning of the body. The opposite end of the body 80 5 from the mouth piece or nipple portion 6 is provided with an annular shoulder 11, and a gradually tapered portion 12, which is adapted to form a friction seat for the combustion chamber portion B of the combined holder and casing. 85

The combustion chamber B is made or pressed from thin sheet aluminum or tin, and the outer surface thereof is colored or painted, to resemble the body of a cigar. 90 The combustion chamber B includes the cylindrical body 13 having its rear end open and its forward end closed and shaped and colored to present the appearance of an artificial cigar ash, as at 14. The rear end 95 of the body 13 is gradually thickened as at 15 and is provided with an inner tapered surface 16 which is adapted to receive or fit upon the tapered friction seat 12. This provides a slip joint which permits a ready 100 or convenient connection or disconnection of the parts A and B. In order to hide the joint between the sections A and B, a band 17 is provided, which is lithographed, stamped or enamelled to give the appearance 105 of an ordinary cigar band. The band 17 is secured in any preferred manner to the outer surface of the body 13 adjacent to the rear end thereof and projects beyond the rear end of the body 13 and is adapted to 110

engage the outer surface of the body 5. This completely hides the connection between the sections A and B.

In use of the improved appliance, the 5 holder portion A is removed from the combustion chamber B and the cigarette C is placed within the metallic nipple 9. The cigarette C is then lit in the ordinary manner and the combustion chamber B is placed 10 on the holder. The device then presents the appearance of a cigar, and effectively prevents falling of the ashes from the cigarette upon the ground. The ash portion 14 of the combustion chamber B is provided 15 with a plurality of perforations 18 for permitting the passage of air into the combustion chamber, and if so desired the body portion 13 of the combustion chamber may be provided with air inlet openings 19 20 throughout its entire length.

From the foregoing description, it can be seen that a novel device has been provided, of exceptionally simple and durable construction, for forming a combined holder 25 and casing for cigarettes. It is to be also understood, that while the device is primarily intended for cigarettes, the same can be used in connection with cigars. Also,

when so desired, the holder portion A may be used as an ordinary cigarette holder and 30 the combustion chamber B dispensed with.

Changes in details may be made without departing from the spirit or scope of this invention; but,

I claim:

As a new article of manufacture, a cigar and cigarette holder comprising a bit portion having a longitudinally extending bore therethrough, a metallic cigar and cigarette receiving nipple fitted in the forward portion of the bore, a combustion chamber section arranged to be detachably associated with the bit section including a hollow metallic body having one end thereof closed and the other end opened, the sections being constructed to simulate the appearance of an ordinary cigar, the combustion chamber having a plurality of air inlet openings formed therein, and an annular outstruck 40 guard flange formed on the nipple and arranged to engage the forward face of the bit portion to prevent the burning of the same by cigars and cigarettes fitted in said bit portion.

WILLIAM C. BRUZGA.
